UNITED STATES PATENT OFFICE.

THOMAS J. LINDSAY, OF INDIANAPOLIS, INDIANA, ASSIGNOR TO LINDSAY AUTO. PARTS COMPANY, OF INDIANAPOLIS, INDIANA, A CORPORATION OF INDIANA.

DRIVING-AXLE STRUCTURE FOR AUTOMOBILES.

Application filed June 25, 1918. Serial No. 241,853.

To all whom it may concern:

Be it known that I, THOMAS J. LINDSAY, a citizen of the United States, residing at Indianapolis, in the county of Marion and State of Indiana, have invented certain new and useful Improvements in Driving-Axle Structure for Automobiles, of which I declare the following to be a full, clear, and exact description.

10 This invention relates to a driving axle structure for automobiles and the like and more particularly to improvements in the driving mechanism supporting structure.

One of the objects of the invention is to 15 provide a driving axle structure formed of a number of independent units which can be readily and independently separated from and reassembled one upon the other.

20 A further object of the invention is to construct an internal gear driving mechanism coupled with the inner ends of the divided axle drive shaft and adapted to be driven directly by the differential train, forming with the internal gear driving 25 mechanism and its supporting frame a unitary structure capable of being inserted within and removed from a main supporting frame or housing as a single unit.

30 A further object of the invention is to mount the internal gear driving mechanism and the differential mechanism as independently connected units, so that the former may be removed from the latter without disturbing or removing the remaining parts 35 thereof.

Further objects, and objects relating to economies of manufacture and details of construction, will definitely appear from the detailed description to follow:

40 I accomplish the objects of my invention by the devices and means described in the following specification. My invention is clearly defined and pointed out in the appended claims.

45 A structure constituting a preferred embodiment of my invention is illustrated in the accompanying drawings, forming a part of this specification, in which:

50 Fig. I is a top plan view of the axle structure embodying the present invention.

Fig. II is a rear elevation of the axle structure with the cap for closing the opening in the main or central housing portion removed.

55 Fig. III is an enlarged, vertical, longitudinal section through the central, or main housing portion and the differential and driving unit, the section being taken on the line III—III of Figs. I, IV and VI.

Fig. IV is an enlarged view showing the 60 differential mechanism and the driving mechanism in full and the axle housing in section, the section being taken substantially on the line IV—IV of Fig. II.

Fig. V is a detail, rear view of the central 65 or main housing portion of the axle structure with the cap removed.

Fig. VI is an enlarged, detail, sectional view through the combined differential and driving unit, the section being taken on the 70 line VI—VI of Fig. III.

In general, the driving axle structure of the present invention comprises five separate and independent units. The main central frame or housing comprises one unit, 75 and the differential, together with the necessary associated parts are mounted in a casting or frame to form a second unit, which in turn is mounted upon an intermediate frame or cage carrying the internal gear 80 wheels and forming a third unit which is detachably mounted in the central main housing comprising the first unit, the latter having a removable cap, covering an opening through which the second and third 85 units as a whole are readily removed. The fourth and fifth units each comprise a tubular casing member having a rotating driven axle shaft section and a road wheel together with the bearings and necessary associated 90 parts. The inner ends of the tubular casings of the last two units are removably connected to the main or central housing member forming the first mentioned unit. Each of the above units may be individually constructed, assembled and adjusted and the complete axle structure may then be produced by the mere assembling or connecting of the units one with another, which in no way involves the adjustment of the bearings 100 or the various parts of the individual units.

For the sake of convenience in the following detailed description, the main or central housing member is designated as unit A, the differential driving mechanism, together with its casing as unit C, the intermediate frame or casing for supporting the last mentioned unit and the internal gear drive 105

wheels as unit B, and the driving axle sections as units D and E, respectively.

The main or central housing member 10 shown in Figs. I, IV and V, which comprises unit A, is formed with a substantially cylindrical portion 11 provided with a forwardly projecting conical portion 12 having the cylindrical end portion 13 provided with the annular flange 14 arranged to be connected 10 to the rear end of the torsion tube (not shown) by means of bolts or other suitable devices. On each side of the central portion of the housing 10 is formed the enlarged annular or substantially cylindrical portions 15 15 from which extend the substantially cylindrical axle housing connecting portions 16. At the rear of the cylindrical portions 15 and 16 and the upper and lower horizontal walls of the casing is a vertically disposed outwardly projecting flange 17 to which is connected the removable cover or cap 18 held preferably by means of the bolts 19, as shown in Fig. I, said cap being provided with the annular portions 20 co-operating 20 with the annular portions 15 to form upon the main housing suitable casings for the internal gear wheels 21, as shown in Figs. I, II and IV. When the cap or cover 18 is disconnected the entire contents of the housing 10 forming units B and C may be removed as a whole or as one complete unit without having to disconnect any other parts of the axle.

The units D and E each comprise a tubular casing member, a rotating axle shaft and a road wheel (not shown), together with the bearings and other necessary associated parts.

The tubular casing member 22 of each of these units may be formed in a single piece or by connecting a number of separate parts constructed in any desired or suitable manner. The tubular member 22 is provided at its inner end with a flange 23 seated in a pocket formed in the projecting portions 16 of the main housing and is secured therein by means of the bolts 24.

Mounted on the outer end of each of the tubular members 22 is a brake mechanism designated generally by the numeral 25 which is not described specifically, it being understood that any well-known form of brake can be used that may be found desirable.

The axle housings 22 and the main housing 10 are adapted to be supported and braced by the rods 26 and 27, the extremities of which are connected in a well-known manner at the outer ends of the tubes 22, as shown in Figs. I and II.

Rotatably mounted in each of the axle housings 22 is a driving axle section 28, which, at its inner end, is provided with a head 29 engaging the bearing ring 30 provided with the ball bearings 31 held by the

ring 32 seated within the bearing box 33 which projects into the enlarged portion of the axle housing 22 and is held against outward movement by the shoulder 34 on the housing, as shown in Fig. IV. The box 33 70 is provided with a thrust bearing comprising the inner and outer rings 35 and 36, respectively, between which are mounted ball bearings 37, the outer ring being seated upon the box and the inner ring upon the bearing ring 30. The box 33 is also provided with a dust guard 38 adapted to encircle the axle shaft 28, as shown in Fig. IV. The bearing box, together with its main and thrust bearings, is inserted upon the axle shaft from the outer end thereof and into engagement with the head 29, as shown, whereby the shaft is held against outward displacement within the housing. The outer end of the axle shaft is provided with a suitable hub 39 85 for carrying a road wheel, (not shown).

Unit B comprising the intermediate frame or cage upon which is mounted the internal gear wheels will now be described. The intermediate frame comprises two mating sections forming, when connected, a substantially cylindrical front portion 40 from which extends an enlarged conical body portion 41 carrying the rearwardly projecting side plates or members 42 having the oppositely extending arms 43 provided with the feet 44 connected with the transverse walls of the main housing 10 by the bolts 45, as shown in Figs. III and IV. The side members at their rear ends are provided with internal circular connecting portions 46 having the abutting flanges 47 connected preferably by the bolts 48, while the front cylindrical portions 40 of the mating sections are provided with the abutting flanges 49 105 connected by the bolts 50, as shown in Fig. IV.

The cylindrical portion 40 is further provided with the annular flanges 51, seated upon the inwardly projecting annular flanges 52 and 53 of the forward cylindrical portion 12 of the main housing 10, as shown in Fig. IV. The front face of the conical portion 41 of the mating sections is seated upon the rear face of the annular flange 53 whereby the mating sections are held against forward displacement in the main housing and against rearward displacement therein by means of the bolts 45 through the feet 44 of the arms 43 which are clearly shown in Fig. III.

Rotatably mounted within the cylindrical portion 40 of the mating sections is the stub driving shaft 54 having the collar or socket 55 provided with the removable slip joint member 56 shown in Fig. IV and adapted to seat within the rear end of the propeller shaft (not shown). The stub driving shaft 54 is further provided with the collars or bearings 57 seated within the cylindrical

is seated in an annular recess formed in the sections of the differential casing at the point where the same are joined together.

The hub of the spider is connected with the ring by the usual number of pins 98 and 99, the differential pinions 100 being journaled upon the latter and adapted to mesh with the beveled gears 88, as shown in Fig. VI.

10 In assembling unit C, just described, the beveled gears 88 and plain bearings 90 are inserted within the hollow journals 85 over which may then be slipped the sleeve bearings 84. The spider with the differential 15 pinions may then be positioned upon one of the mating sections, after which the two sections are brought together and secured by the bolts 76, after which the stub shafts 91 carrying the pinions 92 are driven into 20 position within the sleeves 89 and the unit is complete and ready to be placed in position upon the hubs of the intermediate frame or casing, the mating sections of which are then bolted together and the two combined 25 units inserted within the main housing or casing 10.

It will be understood that when units B and C are removed from the main housing as a single unit, the internal driving gear 30 wheels 21 may be removed from the frame by driving out the pins 66 from the rod 64 and slipping off the retainer 65, which operation can be quickly done without disturbing or removing any of the remaining parts 35 of the unit.

It will also be seen that in removing the intermediate frame or cage from the main housing, the driving shaft 54 contained therein will, at the same time, be withdrawn, 40 since it forms a part of the complete unit.

I am aware that the particular embodiment of my invention, which I have here shown and described, is susceptible of considerable variation without departing from 45 the spirit thereof, and, therefore, I desire to claim the same broadly, as well as specifically, as indicated by the appended claims.

Having thus described my invention, what 50 I claim as new and desire to secure by Letters Patent, is:

1. A driving axle structure, comprising a main housing, a driving mechanism composed of a driving shaft and a differential 55 train adapted to be driven thereby, and a frame or casing for said driving mechanism forming therewith a unit for independent separable attachment within said main housing when the axles are in normal position 60 upon the structure, the said axles being provided with gears on their inner ends and co-operating with the differential train to drive the axles, the said gears being carried by the frame and being separably connected with the ends of the axle.

2. A driving axle structure, comprising a main housing, a driving mechanism composed of a driving shaft, a differential train driven thereby, a driving gear train operatively connected with said differential train 70 and the axle, a frame for said driving mechanism forming therewith a unit for independent separable attachment within said main housing, and capable on removal of carrying with it the gears from the inner 75 ends of the axles, said gears forming part of the driving chain.

3. A driving axle structure, comprising a main housing, a driving mechanism composed of a differential train and a driving 80 gear train operatively connected therewith and a frame or casing for said driving mechanism forming therewith a unit for independent separable attachment within said main housing, and capable on removal of 85 carrying with it the gears from the inner ends of the axles, said gears forming part of the driving chain.

4. A driving axle structure, comprising a main housing, a driving mechanism composed of a drive shaft, a gear train drive, and means operatively connecting said drive shaft and gear train drive, and a frame supporting said driving mechanism and forming therewith a unit for independent 90 separable attachment within said main housing, and capable on removal of carrying with it the gears from the inner ends of the axles, said gears forming part of the driving chain.

5. A driving axle structure, comprising a main housing, a driving mechanism consisting of a differential train and an internal gear drive and supporting means for said driving mechanism forming therewith a unit for independent separable attachment within said main housing.

6. A driving axle structure, comprising a main housing, a driving mechanism consisting of a drive shaft, a differential train and 110 an internal gear drive and supporting means for said driving mechanism forming therewith a unit for independent separable attachment within said main housing.

7. A driving axle structure, comprising a main housing, a frame located between the inner ends of the axle sections, a driving gear journaled upon said frame, an internal driving gear journaled upon the frame and a differential train operatively connecting 120 said gears, said frame, driving gear and internal driving gear forming a unit for independent separable attachment with said main housing.

8. A driving axle structure, comprising a 125 frame located between the inner ends of the axle sections, a driving gear rotatably mounted upon said frame, a differential train rotatably mounted upon the frame and driven by said gear, and a driving gear ro- 130

portion 40 of the mating sections and is held against longitudinal movement by the annular flange 58 on said cylindrical portion, as shown in Fig. VI. At the rear end of the 5 stub shaft 54 and preferably integral therewith is the beveled gear 59 for driving the differential to actuate the internal gears in a manner which will presently be explained.

The rearwardly extending side members 10 of the intermediate frame or casing are provided with the oppositely positioned hubs or bearing boxes 60 having the sleeve linings or plain bearings 61 in which are mounted the journals 62 preferably formed integral 15 with the internal gear wheels 21, as shown in Fig. VI. Extending through the journals 62 of said wheels are the bolts or rods 64, the heads of which are seated in pockets formed in the outer faces of the wheels, the 20 inner ends of the rods being adapted to receive the nuts or retaining members 65 which are secured upon the rods preferably by means of the pins 66, said retaining members having the flanges 67 seated upon 25 the inner faces of the hubs or bearing boxes 60, as shown in Fig. III. The journals 62 of the internal gear wheels are recessed as indicated at 68 and the inner faces of the nuts or retaining members 65 are preferably 30 projected into said recess, as shown in Fig. VI. Each of the gear wheels 21 is provided with two outwardly projecting semi-circular hub or coupling members 69 between which projects the coupling member 70 which is 35 preferably formed integral with the head 29 of the axle shaft 28, said parts being removably connected or coupled, as shown in Fig. II.

The axle shafts are thus flexibly connected with the internal gear wheels and are driven thereby when the latter are rotated. The wheels 21 are provided with the inwardly projecting flanges 71 adapted to receive the internal gear rings 72 secured 45 upon the wheels preferably by means of the pins 73 as shown in Fig. VI. The teeth of the internal gears are cut upon the rings in preference to being formed integral with the flanges of the wheels. Unit B, just described, may be said to comprise the two connected mating sections of the intermediate frame or cage with which are connected the internal gear wheels for rotating the axle sections above referred to.

50 The differential driving mechanism forming unit C will now be described. This unit, taken with unit B may, when connected, be considered as one unit, since it is bodily removable from the main housing forming unit A, previously described. However, when the two halves of the intermediate frame or cage are separated, the differential and inner casing therefor comprise a separate and distinct unit, as will hereinafter 55 be explained.

The differential mechanism is, in general, of a well-known type, although in the particular form shown there are some details of construction which are thought to be new. Unit C comprises the two mating sections 74' and 74 forming a casing for the differential, the section 74 being adapted to receive the beveled gear 75 meshing with the driving pinion 59 on the stub shaft 54 as shown in Fig. VI. The beveled gear 75 and the two mating sections are rigidly connected by the bolts 76, the heads of which are countersunk or set in flush with the outer face of the gear opposite the thrust bearing comprising the inner and outer rings 77 and 78 respectively and the intermediate ring 79 provided with the ball bearings 80. The thrust bearing is slipped over the hub 81 of the right hand frame member 42 of the intermediate frame, as shown in Fig. VI, said hub being threaded externally thereof to receive the internally threaded adjusting ring 82 by which the thrust bearing may be adjusted relatively to the beveled gear 75. The side member of the opposite mating section of the intermediate frame or casing is also provided with an inwardly extending hub, indicated at 83. The hubs 81 and 83 are adapted to receive the plain bearings 84 in which rotate the journals 85, 90 preferably formed integral with the mating sections 74' and 74 of the differential casing, said sections being provided with the annular shoulders 86 which form seats for the flange portions 87 on the inner ends of the sleeve or plain bearings 84. The flanges 87 of said bearings prevent outward displacement of the same by contacting with the inner faces of the hubs 82 and 83.

95 Mounted within the casing formed by the mating sections 74' and 74 are the beveled gears 88 having the outwardly extending sleeve portions 89 projecting into the hollow journals 85 of the casing, said sleeve portions being rotatable in the plain 100 bearings or linings 90 interposed between said hollow journals and said sleeve portions, as shown in Fig. VI.

105 The beveled gears 88 are held against outward displacement by engaging the inner 115 faces of the casing.

110 Projecting through the sleeve portions 89 of said gears and splined theron are the stub shafts 91 having on the outer ends thereof the pinions 92 for driving the internal gear wheels 21, which in turn drive the axle shafts 28. The stub or internal gear driving shafts 91 are recessed as indicated at 93 in Fig. VI, whereby they are considerably lightened and the driving pinions 115 are preferably formed integral therewith.

120 The inner ends of said shafts are reduced to form the journals 94 which are mounted in the sleeve bearing 95 inserted in the hub 96 of the differential spider ring 97 which 130

tatably mounted upon the frame exteriorly thereof and adapted to be driven by said differential train.

9. A driving axle structure, comprising a frame located between the inner ends of the axle sections, a driving gear mounted upon said frame, a differential train mounted upon said frame adapted to be driven by said gear, and a pair of internal drive gears operatively connected with said differential train and removably mounted upon and exteriorly of the frame.

10. A driving axle structure, comprising a frame, a driving gear mounted upon said frame, a differential train mounted upon said frame adapted to be driven by said gear, a pair of internal drive gears operatively connected with said differential train and removably mounted exteriorly of the frame and driving axle shafts having their inner ends operatively connected with each of said internal drive gears.

11. A driving axle structure, comprising a main housing, a frame, and a gear casing rotatably mounted upon said frame and forming therewith a unit for independent separable attachment within said housing when the axle sections are in normal position and gears mounted on the frame and rotated through said casing, the hubs of said gears having a slidable connection with the axle.

12. A driving axle structure, comprising a main housing, a frame, a differential train, a casing therefor rotatable upon said frame, means upon the frame for actuating the casing and an internal drive gear rotatably mounted upon the frame and operatively connected with said differential train, said frame and parts carried thereby forming a unit for independent separable attachment within said housing.

13. A driving axle structure, comprising a frame, a casing rotatably mounted upon said frame, a differential train within said casing, oppositely positioned internal driving gears rotatably mounted upon the frame adjacent the inner ends of the axle sections for driving the same, each of which is operatively connected with said differential train, and a driven gear upon the frame for rotating said casing.

14. A driving axle structure, comprising a frame, a casing having oppositely positioned bearings journaled upon said frame, a differential train in said casing, a shaft adapted to be driven by said differential train, a pinion fixed upon said shaft, an internal driving gear rotatably mounted upon said frame and adapted to be actuated by said pinion, and an axle shaft operatively connected with said internal driving gear.

15. A driving axle structure, comprising a frame, a casing having oppositely positioned bearings journaled upon said frame,

a shaft extending through each of said bearings and provided with a pinion exteriorly of the frame, a differential train within the casing operatively connected with said shafts, oppositely positioned internal driving gears rotatably mounted upon said frame and adapted to mesh with said pinions, an axle shaft removably connected with each of said internal driving gears, and means upon the frame for rotating said casing.

16. A driving axle structure, comprising a main housing, a pair of axle housings removably connected with the opposite sides of said main housing, a frame supported within said housing removable therefrom with the axle sections in normal position and a differential casing rotatably mounted upon said frame, and gears mounted on the frame and rotated through said casing, the hubs of said gears having a slidable connection with the axle.

17. A driving axle structure, comprising a housing having a reduced front portion and a rearwardly extending enlarged portion, and a driving mechanism frame removably mounted within said housing having a supporting member seated upon said front portion and rearwardly extending side members provided with laterally projecting arms secured upon said enlarged housing portion and a drive gear member secured to the lateral projecting arm.

18. A driving axle structure, comprising a housing having a reduced front portion and a rearwardly extending enlarged portion, and a driving mechanism supporting frame removably mounted within said housing, drive mechanism elements secured to the frame, said frame having a supporting member connected with said reduced front portion and rearwardly extending side members connected with said enlarged housing portion, said frame side members being provided with a plurality of sets of aligned bearings for revolvably supporting sets of the driving mechanism elements.

19. A driving axle structure, comprising a housing, a frame removably mounted within said housing having a front supporting member connected with the housing and rearwardly extending side members secured upon and wholly within said housing, said side members being provided with oppositely positioned bearings and a differential casing provided with oppositely extending journals rotatable upon said bearings.

20. A driving axle structure, comprising a housing, a frame removably mounted within said housing having a front supporting member connected with the housing and rearwardly extending side members secured upon said housing, said side members being provided with two sets of oppositely positioned bearings, a differential cas-

- 6
ing having oppositely extending hollow journals mounted upon the bearings of one of said sets, a differential drive within said casing having operating connections rotatably mounted in said hollow journals, pinions carried by said connections, internal driving gear wheels meshing with said pinions and having journals mounted in the other set of bearings, and means for rotating said differential drive casing.
21. As an article of manufacture, an axle drive mechanism housing having a substantially cylindrical front portion provided with a rearwardly extending conical portion carrying spaced circular members connected by transverse walls extending rearwardly from said conical portion.
22. As an article of manufacture, an axle drive mechanism housing having a substantially cylindrical front portion provided with a rearwardly extending conical portion, carrying spaced circular members connected by transverse walls extending rearwardly from said conical portion, said circular members being provided with laterally projecting cylindrical portions adapted for receiving the inner ends of the axle shaft housing.
23. As an article of manufacture, a supporting frame for an axle drive mechanism provided with a substantially cylindrical front portion having an enlarged conical portion terminating in spaced rearwardly extending side members provided with a plurality of aligned bearings and carrying laterally projecting supporting arms.
24. A driving axle structure, comprising a frame provided with a supporting front portion from which extends an enlarged body portion terminating in spaced rearwardly extending side members carrying laterally projecting supporting arms, said side members being provided with two sets of aligned bearings, one of which is adapted to receive the journals of a differential casing, and the other the journals of a pair of internal drive gear wheels.
25. A driving axle structure, comprising a frame composed of two adjacent sections having a supporting front portion from which extends an enlarged body portion terminating in spaced rearwardly extending side members provided with inturned abutting members, said side members being provided with a pair of aligned bearings adapted to receive the journals of a differential driving gear casing, and means connecting said frame sections.
26. A driving axle structure, comprising a frame composed of two connected sections having a supporting front portion from which extends an enlarged body portion terminating in spaced rearwardly extending side members provided with transversely extending connected portions, said side mem- bers being provided with a plurality of aligned bearings and with laterally extending arms forming means by which the rear end of the frame is mounted upon a support.
27. A driving axle structure, comprising a frame having an end supporting member upon which is formed two spaced seating flanges, said end supporting member having rearwardly extending side members, the outer ends of which are provided with transversely extending connected portions and bearings formed upon said side members.
28. A driving axle structure comprising a housing and a driving mechanism within the housing including a differential train and a driving gear train driven thereby, the hubs of oppositely disposed gears in the driving gear train having sliding connections with the inner ends of the axles.
29. A driving axle structure comprising a housing and a driving mechanism within the housing including a differential train, and an internal drive gear train driven thereby adapted for connection with the inner ends of the driving axle sections, the hubs of oppositely disposed gears in the driving gear train having sliding connections with the inner ends of the axles.
30. A driving axle structure comprising a housing and a driving mechanism within the housing including a differential train, and a driving gear train driven thereby, said driving trains being insertable within and removable from the housing as a unit, the hubs of oppositely disposed gears in the driving gear train having sliding connections with the inner ends of the axles.
31. A driving axle structure comprising a housing and a driving gear supporting frame within the housing having one portion carried by a central portion of the housing, and opposite portions connected with the top and bottom walls of the housing.
32. A driving axle structure comprising a cage having a plurality of sets of spaced bearings, a driving gear casing mounted to rotate in one of said sets of bearings, and a thrust bearing for said casing upon said cage, and gears mounted to rotate in another set of the bearings on the cage.
33. A driving axle structure comprising a cage having two sets of spaced bearings, a casing rotatable upon one of said sets of bearings, gears rotatable upon the other set of bearings, a differential train in said casing, means operatively connecting said differential train with said gears for actuating the same, and means for rotating said casing.
34. A driving axle structure comprising a cage having two sets of spaced bearings, a casing rotatable upon one of said sets of bearings, gears rotatable upon the other set of bearings, a differential train in said cas-

ing, means operatively connecting said differential train with said gears for actuating the same, means for rotating said casing, and a driving axle section operatively connected with each of said gears.

35. A driving axle structure comprising a cage having two sets of spaced bearings, a casing rotatably mounted upon one of said sets of bearings, gears rotatably mounted upon the other set of bearings, a differential train in said casing, a pair of shafts actuated by the casing, pinions carried by said shafts for driving said gears, a driving axle section rotatably connected with

each of said gears, and driving means for 15 rotating said casing.

36. A driving axle structure comprising a cage, a casing rotatably mounted within said cage, a differential gear train within said casing, internal drive gears rotatably mounted upon said cage, pinions actuated by said casing for driving said gears, means by which said casing is rotated, and a driving axle section separably connected with each of said gears.

In testimony whereof, I affix my signature.

THOMAS J. LINDSAY.
